UNITED STATES PATENT OFFICE.

EDUARD THEISEN, OF LINDENAU, NEAR LEIPSIC, SAXONY, GERMANY.

DRYING APPARATUS.

SPECIFICATION forming part of Letters Patent No. 393,594, dated November 27, 1888.

Application filed August 4, 1884. Serial No. 139,613. (No model.) Patented in Germany February 21, 1884, No. 29,035; in France March 11, 1884, No. 160,848; in England March 12, 1884, No. 4,798; in Belgium March 19, 1884, No. 64,562; in Austria-Hungary November 11, 1884, No. 38,163 and No. 51,365, and in Russia December 22, 1887, O. S., No. 12,244.

To all whom it may concern:

Be it known that I, EDUARD THEISEN, a resident of Lindenau, near Leipsic, in the Kingdom of Saxony, German Empire, have 5 invented a new and useful Improvement in Apparatus for Drying Goods by Hot Air and Steam; and the following is declared to be a description of the same.

The object of the present invention is to provide a simple and efficient means for drying materials of various kinds by steam, heated air, or gases without the risk of injuring the material by overheating; and to this end my invention relates to new and improved apparatus wherein the materials to be dried are agitated within a vessel which is cylindrical and corrugated or wave-shaped longitudinally, with the corrugations running around the vessel. The vessels are preferably protected, in whole or in part, from the direct action of the hot air or products of combustion by means of hollow jackets, which are supplied with steam that assists in the drying operation.

25 Letters Patent for this invention have been secured to me as follows: in Germany, dated February 21, 1884, No. 29,035; in England March 12, 1884, No. 4,798; in France March 11, 1884, No. 160,848; in Belgium March 19, 30 1884, No. 64,562; in Russia December 22, 1887, (Russian style,) No. 12,244, and in Austria-Hungary, dated November 11, 1884.

The nature of the invention will be understood on reference to the accompanying drawings, in which—

Figure 1 is a vertical cross-section of my improved apparatus. Fig. 2 is a vertical longitudinal section of the same, and Fig. 2^a is a vertical longitudinal section of one inclined 40 vessel in larger size. Figs. 3, 4, 5, 6, and 7 are views of modifications of my apparatus, and Fig. 5^a is an elevation endwise of the drying apparatus shown in Figs. 4 and 5.

In the drying apparatus shown in cross-section at Fig. 1 and on longitudinal section at Fig. 2, *a a* are drying-vessels of corrugated cylindrical, semi-cylindrical, or trough form, which vessels, as shown, are placed one above another, but which might also, if desired, be

placed alongside each other. Each corrugated vessel will be surrounded by either a whole or a half cylinder, *b*, in such a manner that there will be a steam-space, *c*, between them. Examples of the different modes of carrying out this arrangement of steam-spaces are shown 55 in the three "tiers" in Figs. 1 and 2. The uppermost corrugated vessel is in the form of a half-cylinder, *a*, and is surrounded with an entire cylinder, *b*. The central and lowermost corrugated vessels are in the form of complete 60 cylinders *a*, the former of which is surrounded by an entire cylinder and the latter by a half-cylinder, *b*. These outer cylinders, *b*, which, like the vessels *a*, may be constructed of plain or corrugated plates or sheets of metal, are 65 provided with brackets *d*, resting upon supporting-girders fitted into the side walls. In the arrangement shown at Figs. 1 and 2 the hot-air current entering at *g* passes upward in the direction of the arrows and plays around 70 the cylinders *b*.

Into each of the steam spaces *c* a tube, *e*, provided with a valve, *e'*, opens, which tubes intercommunicate by means of a common main tube, *f*, situated outside the apparatus and provided with a pressure-gage, *f'*. Through this tube *f* and the tubes *e*, each of which is provided with a separate stop-cock, water is admitted to the steam-space up to a level with the mouths of the tubes *e*, which water will be 80 converted into vapor by means of the hot air entering at *g* and ascending in the direction of the arrows, and the steam or vapor becomes condensed on the large drying-surfaces presented by the corrugations of the vessels *a*, 85 and this condensed water will be again vaporized by means of the hot air circulating around the steam-space. In this way a good working equable drying temperature is obtained in the vessels or barrels *a*, through which the materials or goods to be dried are passed. Passing centrally through each of the vessels *a* is a shaft, *h'*, supported at its ends in suitable bearings, and upon and keyed to this shaft are wheels having arms *h*², and upon and secured to the periphery of these wheels are longitudinal bars of nearly the length of the vessel *a*, and there are blades or stirrers *h* secured

to these bars, the edges of which are pointed to correspond with the interior corrugated surface of the vessel *a*. The goods or materials to be dried are passed through the hoppers *w* into the vessels *a*, where they are constantly agitated by being lifted by the blades or stirrers *h*, and such materials slide back off of such blades and are scattered about and shifted and gradually worked from the hoppers 10 through the vessels *a* to the spouts *s*. The vessels *a* and their shafts *h* are slightly inclined from the hoppers *w* to the spouts *s* to facilitate the delivery of the goods being dried, as shown in the drawings, Fig. 2^a. This inclination should be about one in seventy.

I have shown in the lowermost cylinder of Fig. 2 a spiral conveyer, *i*, composed of a twisted blade of metal, surrounding, attached to, and moving with the shaft *h*, and of an external diameter almost identical with the interior of the corrugations of the vessel *a*; and I prefer to employ this spiral conveyer *i* to move the agitated material progressively toward the delivery end, where it is discharged 25 by the spouts *s*. The vapors formed in the barrels or vessels *a* from the drying of the materials or goods will pass off through the channels *v*.

Instead of generating the steam in the spaces 30 *c*, a boiler may be arranged in the apparatus either as a steam-generator or recipient for steam led thereto, and from which the steam will be led to the spaces *c* and be there superheated by means of the current of hot air, 35 while the water of condensation flows back to the boiler.

If the boiler is built into the apparatus, steam can be generated therein by means of hot gases of combustion led thereto, which 40 gases will then pass through the various tiers, either vertically or horizontally, until they escape into the chimney. If the boiler is provided with a direct-heating furnace, the products of combustion may be utilized as hot 45 air for the apparatus. The boiler may also, of course, be arranged outside the drying apparatus, and steam may be carried thereto from any approved source.

In the lower portion of the apparatus, Fig. 50 3, the boiler *k* is shown in place. Where a cylinder or boiler, as *k*, is used without a fire beneath it, steam may be supplied by the pipe *l* from an outside source. A tube, *f*², leads the steam from the boiler to the tube *f*, which 55 is provided with a pressure-gage, and the tubes *e* lead the same into the spaces *c*, surrounding or partially surrounding the barrels *a*, in which spaces the steam will be superheated by means of the ascending current of 60 hot air and will impart its high degree of heat to the drying-surfaces. The tubes *x* are connected to the lowermost portions of the cylinders *b*, and are inclined and communicate with the tube *x'*, so that the water of condensation 65 may flow back into the boiler *k*.

m is a furnace in case steam is to be generated in the boiler, the products of combustion from

which will be led upward for the purpose of superheating steam admitted into the spaces *c*, circulating on its passage around the cylinders *b*. In this case the hot-air admission channel will not be required; or, if the arrangement is effected to meet both cases, the latter must be closed during the operation of the furnace *m*. It is also advisable to adapt for each space *c* 75 separate tubes for the admission of steam and the carrying off of the products of condensation, in which case the exit-tube for the water of condensation should be placed, not at the lowest possible point, but somewhat 80 higher in the space *c*, in order to maintain a certain height of water of condensation therein, which, by the action of the surrounding hot air, will be again converted into steam. Further, the drying-vessels constructed of entire 85 corrugated or wave-shaped cylinders, with or without surrounding steam space, may be employed without the addition of blades, in which case the drying-barrels themselves will be arranged to rotate. This arrangement, which 90 is shown in cross-section at Fig. 4 and in longitudinal section at Fig. 5, is best adapted for small drying establishments.

The drying-vessels *a*, of corrugated or wave-shaped surface and cylindrical form, are fixed 95 on a shaft, *n*, by means of the cross-frame *n'*, and are suitably arranged within a hot-air chamber, and are capable of being set in rotation by means of a crank-handle or by mechanical driving arrangements situate outside the said chamber. In the drawings these rotating vessels are shown, by way of example, as fitted in a heating-chamber of brick-work, the front side of which is closed in by a pair of doors, *g g*, (shown in Fig. 5^a.) which, 100 upon being opened, admit of the removal of the vessels therefrom. The upper drying-vessel, which is at some distance from the heated gases, is represented as merely an entire corrugated cylinder, *a*, while a complete cylinder, *b*, is arranged around the lower vessel, so that a steam-space, *c*, is formed, into which steam or water will be admitted through the shaft *n* (which is hollow at its front end) and the short tube *o*. At one end the rotating drying-vessels *a* may be provided with a cover, *a'*, for the purpose of filling and emptying the same. When the rotating vessels are not protected by steam-spaces, the covers may be fitted onto the periphery, and the fitting and 110 emptying may be effected in different ways, dependent upon whether the vessels are removable or not. Rotating steam-heated drying-vessels could also be adapted to open hearths or fire-places.

A further modification of drying apparatus with corrugated drying vessels or chambers is represented at Figs. 6 and 7.

The semi-cylindrical vessels *a*, formed of hollow castings arranged one beside another, or of corrugated sheet metal or of single sheets of metal bolted together and provided with steam-admission pipes *b*² and exit-channels *c*² for the escape of the water of condensation,

and in which blades h rotate, will be closed in at top. These so-formed cylinders, when the apparatus, as in Fig. 6, is constructed with a single drying-vessel a , will be surrounded 5 with a closed jacket, while on the other hand, when, as in Fig. 7, several drying vessels or cylinders a are arranged in proximity to one another, they will be surrounded by a closed rectangular casing. The hollow spaces thus 10 formed between barrel and jacket or casing serve for the heating of the air contained therein by means of the heat radiating from the hot steam in the hollow portions of the drying-vessels, which heat passes at one side 15 through the tubes d into the interior of the drying-vessels a for direct action upon the material under treatment and out of which it will be drawn on the other side through a flue or chimney. 20 Having now particularly described and ascertained the nature of my said invention and in what manner the same is to be performed, I declare that I am aware that corrugated or waved surfaces heated from below 25 have been used in combination with rotating blades or stirrers above them, and I do not claim such drying apparatus as my present invention.

I claim as my invention—

30 1. In a drying apparatus, the combination,

with a cylinder, a , having a corrugated or undulating surface and containing the material to be dried, of revolving stirrers within said cylinder, the edges of whose blades are corrugated to correspond with the surface of the 35 cylinder, a steam-jacket, c , outside of said cylinder, and a pipe, e , for supplying steam to said jacket, and a flue outside of the cylinder a and jacket c for heated air, substantially as specified. 40

2. In a drying apparatus, the combination, with a cylinder, a , having a corrugated or undulating surface and containing the material to be dried, of revolving stirrers within said cylinder, the edges of whose blades are corrugated to correspond with the surface of the 45 cylinder, a steam-jacket, c , outside of said cylinder, and a pipe, e , pipes f and f^2 , a hot-air flue outside of the cylinder a and jacket c , a boiler, b , and furnace m , for supplying steam 50 to the said jacket and heated air to said flue, substantially as specified.

In testimony whereof I have hereunto set my hand, this 11th day of January, 1884, in the presence of two subscribing witnesses.

EDUARD THEISEN.
